UNITED STATES PATENT OFFICE.

HUGH DUNN, OF FALKIRK, SCOTLAND.

MACHINE FOR FINISHING BOOK COVERS.

Application filed March 10, 1927, Serial No. 174,253, and in Great Britain March 13, 1926.

This invention relates to machines for finishing the rounded back of books of miscellaneous sizes and thicknesses by the application of lining, lettering or ornamentation. In the case of lining, "blind" or other lines such as, for instance, gold or ink lines may be applied (all of which are herein referred to as lining for convenience) while in the case of lettering, letters, numerals and any other distinctive characters may be applied (all of which are herein referred to as lettering for convenience).

The object of this invention is to provide a machine which will effect ordinary lining, lettering or ornamenting in a better manner than heretofore, and which can also be used alike for "blind", gold or ink work.

The features of this invention will be apparent from the following description and will be more particularly pointed out in the claims.

Referring to the drawings:—

Fig. 1 is a side elevation of the machine.

Fig. 2 is a section on line II—II in Fig. 1.

Fig. 3 is a section on line III—III in Fig. 2.

Fig. 4 is a fragmentary view illustrating the positioning devices.

Fig. 5 is a longitudinal sectional view of the type carrier removed.

Fig. 6 is a side elevation of the type carrier.

Fig. 7 is a sectional view on line VII—VII in Fig. 6.

Fig. 8 is a longitudinal sectional view of the type carrier.

Fig. 9 is a sectional view on line IX—IX in Fig. 7.

Figs. 10 and 11 are side elevations of the type.

Fig. 12 is a side elevation of the retaining blocks.

Fig. 13 is a plan view of an electrical heating appliance for the tools.

Fig. 14 is a side elevation thereof showing the electrical heating appliance attached to the machine.

Fig. 15 is a perspective view of a device for heating the tools separately from the machine.

Fig. 16 is a perspective view of an appliance for handling the hot tools.

Fig. 17 is an inverted plan view of an alternative form of type carrier.

Fig. 18 is a section on line XVIII—XVIII in Fig. 17.

Fig. 19 is a section on line IXX—IXX 55 in Fig. 17.

Fig. 20 is a longitudinal sectional elevation.

Fig. 21 is a perspective view of the type holder removed from the carrier.

Figs. 22 and 23 are side elevation and rear 60 elevation perspectively of a machine operated by power.

Fig. 24 is a fragmentary sectional side elevation of the machine shown in Fig. 22.

In the construction illustrated in Figs. 1 65 to 3, the apparatus comprises a rectangular box-like main frame 1, having two clamping members 2—3 adapted to receive and hold the book 4; at least one of which clamping members is movable, preferably under the 70 control of a quick-acting screw 5 operated from a hand wheel 6 on the exterior of the main frame. A setting gauge 7 is provided on the clamping members adapted to position the book in relation to the tools. 75

On the top of the frame 1, at one end thereof, is fixed two spaced bearings 8 carrying a bar 9 mounted on trunnions 9^a so that the bar serves as a pivot for a flat rectangular guide frame 10. This guide frame extends 80 from one side of the machine across the top of the main frame and is free at its other end 11.

Slidably mounted on the guide frame is a carriage 12 having downwardly extending 85 lugs 13 which project into the main frame and carry a fixed projection 14 on one side and a movable projection 15 on the other side. The projection 15 is screwed so that it can be retracted to receive detachably the spindle 22 90 carrying the finishing tool which will be hereinafter explained. The spindle has counter-bored ends 28 with which the projections 14 and 15 engage.

The carriage has a pin and slot connection 95 at each side thereof with a lever-like frame, the carriage being preferably provided with projecting pins 17 in the ends of the transverse bar 16 which engage in slots 18 in the frame. This lever frame consists of two bars 100 19 one at each side of the main frame pivotally mounted at 20. These bars extend upwardly and may be provided with a number of transverse rods, only one marked 21 however is shown. Where more bars than one 105 are provided these are disposed at different distances from the fulcrum and constitute a number of handles any one of which can be

selected by the operator so as to vary the leverage.

The guide frame 10 is provided with rearwardly extending spindles 23 carrying counter balance weights 24, which are adjustable thereon, being clamped in their adjusted position by the set screws 24^a, said weights acting to counter balance the weight of the tool carriage and other parts mounted on said frame.

10 The carriage for the tools is so arranged that it is rocked on the guide frame and thereby moved from one side to the other of the clamping members under the action of the lever frame. When the tools are idle, such as when a book is being placed into the clamping members, preparatory to lining, the tools will lie at one side of the clamping members. In a position, thereof, directly beneath this idle position of the tools an electric heating device 25 is disposed so as to heat the tools. This electric heating device which is shown more clearly in Figs. 13 and 14, consists of two lengths of resistance wire 54 wound on insulating material 55 and mounted on an insulating base member 56 fixed to a metal frame 57 so mounted on the machine that it occupies the position aforesaid but is adjustable towards or away from the tools. The metal frame may be secured in its adjusted position by means of the screws 58. The resistance wires are connected to a source of supply through a series-parallel switch adapted to put the lengths of resistance wire into circuit singly, or collectively in series or in parallel so as to give thereby three grades of heat.

40 In order to regulate the pressure of the lining tools as they move over the book, the free end 11 of the guide frame can be pressed down to the required extent. A foot treadle 26 is provided which may be used for this purpose, this treadle being connected to the free end 11 of the guide frame 10 by means of the connecting links 27 and the bolt 28 fixed to the end frame member 11.

45 The finishing tool which is used for lining, lettering or ornamenting the back of the book comprises the cylindrical type carrier shown more particularly in Figs. 5 to 9. This device consists of a cylinder 30 having a number of annular ribs 31 these ribs having a laterally extending flange 32 on one side extending around slightly more than half the circumference thereof, the remainder of the ribs being flat sided as shown. To this cylinder is adapted to be fixed type 33, this type being made of the form shown in Figs. 10 and 11, having the two opposite side faces 34—35 tapering as shown, having another face 36 formed with a notch 37 and having the remaining face 38 formed with a shoulder 39. The type is so arranged that it can be pushed endwise in between the flat sided portions of the ribs and then slid round into the position shown

in Fig. 7, the flange 32 engaging the notch 37 to retain the type. The type is clamped in position by means of the blocks 40 shaped similar to the pieces of type except that they are not so high (see Fig. 12) these blocks having a flange 41 and a set screw 42 and having a screw 43 to clamp the type in position. These blocks are slid in between the same ribs as the type and then the set screw 42 is screwed down to engage with an adjacent rib and thereby fix the blocks in position upon the cylinder.

50 The form of type shown is advantageous in that owing to its tapering sides it beds together on the type carrier, in that it can be quickly applied to the type carrier by hand and having an interengaging flange and notch at one side only it must always be placed in the correct way on the type carrier.

55 For lining or ornamenting, long pieces of type 44 are used, the ribs on the lower part of the type case being made flat for nearly half their circumference, to enable these pieces to be inserted therebetween, as indicated in dotted lines in Fig. 9, and then slid round into the position shown in full lines in Fig. 9; the pieces 44 being shaped and notched similar to the other type pieces. These pieces of type are each sufficiently long to produce one line on the back of the book. These pieces 44 are also held in place by blocks 40. The carrier will take all the type necessary for lining, lettering and ornamenting the whole back of a book, at one operation.

60 Lines 45 are engraved on the periphery of the ribs to facilitate the positioning of the type thereon.

65 The type case is provided with a central bore 46 by which it can be slid on to the spindle 22 and clamped in position by the screws 47.

70 An alternative and preferred construction of the type carrier is shown in Figs. 17 to 21. In this form the carrier comprises a cylinder 150 having a series of spaced radial ribs 151 having flat, parallel sides around their whole circumference. Between these ribs are mounted the type or a holder therefor, the type or holder being forced in between the ribs and being retained by the frictional engagement of the parts. In the drawing one of these holders is shown in position in Figs. 17-20 and detached in Fig. 21. This holder comprises a main side member 153, having two fixed spacing lugs 154—155, one at each end thereof, and having an auxiliary side member 156 fixed at its ends only to the lugs 154—155 by the rivets 157 so that it can flex outwardly, and thus be distended.

75 The main side member is provided with a laterally extending flange 158. The type 159 and retaining blocks 160 and 161 are constructed similar to those shown in Figs. 10, 11 and 12 except that the former are without the

shoulder 29 and the retaining blocks are modified as shown. With this arrangement the type can be quickly assembled in the holder by inserting it with its tapered sides against 5 the side members of the holder (as shown in dotted lines in Fig. 21) and then turning it through 90° so that the flange 158 engages in the notch 37. After all the type for one row of lettering has been set up in this manner 10 the blocks 160 and 161 are moved up to hold the type firmly together in its proper position, the said blocks being clamped by the screws 163 and then this holder is forced into position between the ribs. The screws 163 and 164 are then finally tightened up. In 15 this way not only is the type held absolutely rigid but on detachment for the carriage it can be quickly extracted and other type substituted therefor. Where large pieces of type 20 are used as that marked 168 provided for lining this can be mounted directly in between the ribs 151.

The spindle may also be heated internally as shown in Fig. 5, the spindle 22 being made 25 hollow and the electrical heating device arranged inside. This electrical heating device may consist of a coil of resistance wire 170 extending between the two terminals 171 and 172 fixed one in each end of the spindle. 30 The terminals each consist of an insulating bush 173 composed preferably of mica discs fitting snugly in the spindle and carrying a metal socket 174 having a pin 172 at its inner end which passes through the insulating bush and is screwed to receive a nut 175 which 35 serves to clamp the insulating bush to the socket and also to attach one end of the resistance wire thereto. Plugs 176 are provided fixed on the ends of the electrical supply leads 40 178 adapted to engage in the socket. The set pins 177 serve to fix the terminals within the hollow spindle. The rod of resistance wire 170 is surrounded by insulating bushes 179 disposed in abutting relationship in the hollow spindle. 45

The type carrier is supported in a position in which the type extends downwardly as indicated in Fig. 3 so that by reciprocating the slide 12 on the frame 10 the type carrier 50 and its spindle will be given a rocking movement as the type carrier traverses the book due to the engagement of the type with the back of the book, the spindle being rotatable.

In order to ensure that the lettering or 55 other ornamenting matter is placed symmetrically upon books of different thickness the following apparatus shown in Fig. 4 is employed. A member 48 forming a ridge is provided, arranged to be detachably fitted to the flat sided portion of the ribs on the type case, in the centre thereof, this ridge co-operating with a screw pointer 49 (Fig. 4) fixed on the carriage to position the type carrier on the machine. After the type carrier 60 has been positioned in this way, the

screw pointer 49 is retracted, out of engagement with the ridge, to enable the type carrier to roll freely. A graduated member 50 is also provided, said member having a boss 51 by which it is mounted upon the frame member 10 and fixed by the pinching screw 52, this graduated member co-operating with the front edge 53 of the slide 12, which edge acts as an index mark, to show the position of the carriage for each thickness of book. 75 In the arrangement shown in Fig. 3 a book 2 inches thick is clamped in position and the slide is moved until the edge 53 is opposite the 2 inch mark on the scale when the type will be positioned centrally over the back of the book. In use the type will be positioned in this manner while the frame 10 is in its raised position and subsequently the frame 10 will be depressed to bring the type into contact with the back of the book after which 80 the slide will be reciprocated slightly to rock the type carrier and the type over the back of the book to either side of the central position. 85

It is not essential that the operation be 90 carried out in the manner specified above, but the tools may be rocked in a similar manner to that specified in the preceding paragraph except that the rocking movement may be commenced at one side and finished at the 95 other. In fact this method is found preferable in certain circumstances. It will be understood that in the latter case the position of the member 48 must be altered so as to bring the type into the required position. 100

As shown in Figs. 1-3 a vertically adjustable support 120 for the book may be provided beneath the clamps 2 and 3, this being 105 slidably mounted on guides 120^a and supported and moved by means of links 121 provided at each corner and so connected by the lugs 121^a and transverse members 121^b to nuts 122 engaging the right and left hand screw threaded parts 123 and 124 of the shaft 125 mounted in a bracket 127 and operable by 110 the hand wheel 126 as to raise or lower the support according to the direction in which the screw is rotated. This support facilitates the positioning of the book in the machine and is particularly useful for heavy 115 books.

The above described methods of heating the tools are extremely useful in repetition work, i. e. work where the tools do not require to be constantly altered, but with other classes of work, it is preferred to employ another different form of heating device. This consists of a metal box 140 (see Fig. 15) having a hinged lid 141 and a lining 142 of insulating material, electrical heating elements or gas or other heating means (not shown) being located in the bottom and being covered by the perforated tray 144 while the top of the box and the lid are recessed at 145 and 146 to receive the tools. In this 130

method the tools can be made up or composed and placed in the box to be heated and maintained at the proper heat until required for use. In this way the machine is not delayed while the tools are being heated, cooled and changed. With this apparatus some means is required to enable the operator to handle the hot tools. A suitable device for this purpose is shown in Fig. 16 and consists of two hook members 147 fixed at either end of two spaced rods 148—149, the hook being adapted to engage around the spindle near the ends thereof.

For gold work the gold leaf would be first applied to the back of the book, and for ink work the type will be inked.

In Figs. 22 and 23 mechanism is shown for driving the machine by power, in which case a driving shaft 100 fixed to the back of the machine has loosely mounted thereon the driving belt pulley 101 continuously driven when the machine is in use by a belt 104 from a prime mover, said pulley 101 being adapted to be clutched and declutched from the driving shaft by a dog clutch shaft 102. This driving shaft 100 has two pinion wheels 105, one at each end, which mesh with toothed wheels 106 fixed on top of the machine frame and these toothed wheels 106 are provided with links 107 connected to the upstanding lever frame 19 adapted on rotation of the toothed wheels to reciprocate the said lever frame. The dog clutch 102 is provided with a lever 108 connected at one end thereto, pivoted at 109 intermediate its ends and having a weight 110 (or spring) at its free end; said weight (or spring) tending to disengage the clutch. The clutch is operated through said lever by means of an operating handle 111 (Fig. 22) mounted at the front of the machine, fixed to a cranked rod 113 extending to the back of the machine and serving, on operation of the handle, to raise the weighted end of the lever 108 and move the clutch into its engaged position. This starts the lever frame 19 and the carriage 12 reciprocating and this carriage is provided with an extension 114 which engages with a control lever 115 rockably mounted on the driving shaft 100 and having a projection 116 on its lower end adapted to engage beneath the clutch lever to retain it in its raised position.

The arrangement is such that when the machine is idle the projection 114 on the carriage holds the control lever in an inoperative position shown in dotted lines in Figs. 22 and 24 but as the carriage begins to move the lever 115 is released and this then moves under the action of the spring 130 and brings the projection beneath the clutch lever. The carriage then continues to move forward and then backward and as it comes to the end of its rearward stroke the extension 114 thereon rocks the control lever so as to trip the clutch lever which by reason of the weight disen-

gages the clutch. By this means the carriage reciprocates forward and backward once and then automatically stops.

The links may be detachably connected to the upstanding lever frame so that the power driven means can be readily disconnected and the machine made manually operable.

The motor 118 may be placed on an under frame 119 for the machine, and act to drive the loose pulley 101 by belt chain or other gearing. Where necessary for reducing the speed of the drive to the machine, the motor drives the pulley through suitable reduction gearing such as a counter shaft 119 having pulleys 112 of a size necessary to give the required reduction of speed. This reduction gearing may also be mounted on the under frame.

This mechanical drive is more particularly applicable to blind work, but it may also be used with other classes of work. In connection with gold work a delicate adjustment of the counter balance weights must be made.

This power drive in the form shown is applicable for lining and certain ornamental work where the matter does not require to be placed in a certain position on the back of the book. It will be readily apparent to anyone skilled in the art that the mechanism could be readily adapted to lettering or other ornamental work, or without alteration the lettering or ornamental work can be done by hand.

I claim:

1. A machine for the purpose specified, comprising, means for holding a book, means for carrying type, said means being so constructed as to receive all the type necessary to finish the whole back of the book, means for reciprocating the said type carrying means, means pivotally mounted at one end and extending across the machine above said book holding means and being manually operable at its free end, for moving the type carrying means towards the book during their reciprocation so that the pressure can be suited to the work, and means for positioning the means for carrying type relative to the back of the book.

2. A machine for the purpose specified comprising, stationary means for holding a book, a frame pivotally mounted at one end and extending across the machine above said book holding means and being manually operable at its free end for moving it towards the book, a carriage reciprocably mounted on said frame, means for reciprocating said carriage, means for carrying type, said means being so constructed as to receive all the type necessary to finish the whole back of the book, means for detachably mounting said type carrying means on said carriage and means for positioning said type carrying means relative to the book.

3. A machine for the purpose specified

comprising, stationary means for holding a book, a frame pivotally mounted at one end and extending across the machine above said book holding means and being manually operable at its free end for moving it towards the book, a carriage reciprocably mounted on 5 said frame, means for positioning said carriage relative to the book so as to suit books of different sizes, means for reciprocating 10 said carriage, means for carrying type, said means being so constructed as to receive all the type necessary to finish the whole back of the book, means for detachably mounting said type carrying means on said carriage 15 and means for positioning said type carrying means relative to the book.

4. A machine for the purpose specified, comprising, means for holding a book, means for carrying type, said means being so constructed as to receive all the type necessary to 20 finish the whole back of the book, means for reciprocating the said type carrying means, means pivotally mounted at one end and extending across the machine about said book 25 holding means and being manually operable at its free end, for moving the type carrying means towards the book during their reciprocation so that the pressure can be suited to the work, means for positioning the means 30 for carrying type relative to the back of the book and means for heating said type carrying means.

5. A machine for the purpose specified comprising, stationary means for holding a book, a frame pivotally mounted at one end and extending across the machine above said book holding means and being manually operable at its free end for moving it towards the book, a carriage reciprocably mounted on 35 said frame, means for reciprocating said carriage, means for carrying type, said means being so constructed as to receive all the type necessary to finish the whole back of the book, means for detachably mounting said type carrying means on said carriage, means for 40 positioning said type carrying means relative to the book and electrical means for heating said type carrying means.

6. A machine for the purpose specified comprising, means for holding a book, finishing tools, power driven means for reciprocating said finishing tools and means pivotally mounted at one end and extending across the machine above said book holding means 55 and being manually operable at its free end for moving the finishing tools towards the book during their reciprocation so that the pressure can be suited to the work.

7. A machine for the purpose specified comprising, means for holding a book, finishing tools, power driven means for reciprocating said finishing tools, means for starting said power driven means, means for interrupting said driving means at the end of one 60 reciprocal cycle and means pivotally 125

mounted at one end and extending across the machine above said book holding means and being manually operable at its free end for moving the finishing tools towards the book during their reciprocation so that the 70 pressure can be suited to the work.

8. A machine for the purpose specified comprising, means for holding a book, finishing tools, a carriage for said tools mounted to reciprocate above said book holding means from a position on one side to a position on the other side thereof, power driven means for reciprocating said carriage, means for starting the said power driven means, means on said carriage to stop said power 80 driven means as the carriage moves back to its initial position and means pivotally mounted at one end and extending across the machine above said book holding means and being manually operable at its free end for moving the finishing tools towards the book during their reciprocation so that the 85 pressure can be suited to the work.

9. A machine for the purpose specified comprising, means for holding a book, finishing tools, a carriage for said tools mounted to reciprocate above said book holding means from a position on one side to a position on the other side thereof, a driving shaft, a driving pulley loosely mounted on said shaft and 90 adapted to be continuously driven, a clutch for clutching and declutching the pulley to said driving shaft, means driven by said shaft adapted to reciprocate said carriage, a starting device adapted to engage said 100 clutch, a control lever adapted, after the carriage has begun to move forward, to retain the clutch in its engaged position and as the carriage approaches the end of its rearward movement to disengage said clutch and thereby stop the machine, and means pivotally mounted at one end and extending across the machine above said book holding means and being manually operable at its free end for 105 moving the finishing tools towards the book during their reciprocation so that the pressure can be suited to the work.

10. A machine for the purpose specified comprising, means for holding a book, finishing tools, a carriage for said tools mounted to reciprocate above said book holding means from a position on one side to a position on the other side thereof, a driving shaft, a driving pulley loosely mounted on said shaft and adapted to be continuously driven, a clutch for clutching and declutching the pulley to said driving shaft, means driven by said shaft for converting rotary into reciprocating motion, said means being connected to said carriage so as to reciprocate the same on rotation of the shaft, a clutch lever, weighted and arranged so as normally to retain the clutch in its disengaged position, an operating device adapted to move said clutch lever so as to engage the clutch, 110 120 125 130

a control lever adapted to hold the clutch lever in its engaged position, means on said carriage to trip said control lever at the end of each reciprocating cycle of the carriage so as to allow the clutch lever to disengage the clutch and thereby stop the machine and means pivotally mounted at one end and extending across the machine above said book holding means and being manually operable 10 at its free end for moving the finishing tools towards the book during their reciprocation so that the pressure can be suited to the work.

11. A machine for the purpose specified

comprising, means for holding a book, finishing tools, means for reciprocating said finishing tools, means pivotally mounted at one end and extending across the machine above said book holding means and being manually operable at its free end for moving the finishing tools towards the book during 15 their reciprocation so that the pressure can be suited to the work, and a foot treadle connected with the free end of said pivotally mounted means.

In testimony whereof I affix my signature.

HUGH DUNN.
